January 22, 1937, Serial No. 121,777

6 Claims. (CL 102—2)

This invention relates to aerial bombs for penetration and demolition, and has for an object to provide improved structures for guiding and directing the bombs.

A further object of the invention is to provide improved means for producing detonation.

A further object of the invention is to provide improved means for locking the various detonating devices against accidental discharge prior to launching from an airplane or the like.

A further object of the invention is to provide improved means coaxing with the aircraft for maintaining the bombs in inactive condition.

A further object of the invention is to provide an improved type of streamlining for bombs, whereby the descent in the drop is accelerated.

A further object of the invention is to provide an improved type of bomb having an initial discharge of an explosive, thereby projecting a second missile to a further distance intended for penetrating purposes, said second missile being provided with means for subsequently igniting and exploding for demolition purposes.

A further object of the invention is to provide a bomb with fins serving for guiding and stabilizing with improved structure for cambering the fins to provide a whirling action of the bomb bodily upon its longitude.

A further object of the invention is to provide an improved type of gyroscope connected with the bomb, with propeller means actuated by the descent for driving the gyroscope for stabilizing the trajectory of the bomb.

The invention, therefore, comprises a bomb body having a charge of explosive mounted therein, with a second body projected from the first mentioned or main body by the said explosion, said second body having an explosive charge therein adapted to be ignited subsequent to its discharge from the main body, either by the first mentioned explosion, or by impact, said body being provided with fins at its normally rear end, in one instance, the fins being provided with means for cambering to an angle to provide a rotary action of the bomb upon its major axis during its descent, and in another instance, a similar effect produced by a gyroscope located in the rear of said bomb, controlled by a propeller at the rear of said bomb, said gyroscope tending to stabilize the line of travel, and with improved means for igniting initially the main charge in the body of the bomb to propel therefrom the secondary explosive body for penetration and demolition purposes.

The drawings illustrate several embodiments

of the invention, and the views therein are as follows:

Figure 1 is a view in longitudinal diametrical section through one type of bomb.

Figure 2 is an enlarged detailed view of that part of the bomb shown at Figure 1, enclosed within the circle 2.

Figure 3 is a view of the bomb shown at Figure 1; end elevation is indicated at arrow 3 at Figure 1.

Figure 4 is a view in side elevation of the vanes in the type shown at Figure 1, after being cambered to produce rotary action of the bomb during descent.

Figure 5 is a view in detailed side elevation, 15 of one of the locking means employed for locking the vanes against cambering.

Figure 6 is a sectional view taken on line 6—6 of Figure 2.

Figure 7 is a view on a longitudinal diametrical plane of a modified type of bomb.

Figure 8 is an enlarged detailed view of a section of the type shown at Figure 7 and included within the circle 8 of Figure 7.

Figure 9 is a detailed view partly in elevation and partly in section of the part enclosed within the circle 9 of Figure 7.

Figure 10 is an enlarged detailed view of the part enclosed within the circle 10 of Figure 7, and

Figure 11 is an end view of the bomb as indicated by the arrow 11 at Figure 7.

Like characters of reference indicate corresponding parts throughout the several views.

The bomb of the type shown at Figure 1, more especially, is provided with a body 20 which will 35 preferably be cylindrical, and is provided with a chamber for receiving an explosive charge at 21. The body 20 will obviously be of heavy stress-resisting material, to accommodate the explosion of the explosive mixture 21.

Within the explosive mixture 21, preferably along the axis of the body, a booster 22 is provided, of substantially the usual and ordinary type, having a primer 23 in communication with the booster in the manner well known in the art. 45 The body will preferably be provided with a conical shell 24, largely for the purpose of streamlining the organization, and at the apex of this cone, a nut 25 will engage the rod 26 which carries the firing pin 27. The firing pin is normally supported out of engagement with the primer 23 by a spring 28, but the spring is so arranged as to yield under impact when the nut 25 has been removed, and to thereby engage the primer 23 with sufficient force for detonating said primer. 55

For the purpose of removing the nut 25 after the bomb has been launched, fins 29 are provided integral with or rigidly connected to the nut, whereby the air slip tends to rotate the fins 29 and nut 25 to release the rod 26 to permit the detonation upon impact.

The conical shell 24 also supports the fins 30 which are pivoted to said shell at 31, whereby when said fins are released, they may automatically move to the position shown at Figure 4, but means is provided to accomplish such movement positively.

The aircraft rack is provided with means indicated only in dotted lines at 32, tending to hold the fins 30 in longitudinal alignment while the bomb is retained in the rack. Furthermore, the fins are held by means of levers 33 rigidly connected with the pivots 31 and engaging in slots 34 in a block 35 slideable upon an angular sleeve 36 through which sleeve extends the rod 26.

The locking just above mentioned is provided by a collar 37 mounted to slide upon the angular sleeve 36 but held by a set screw 38 which may be loosened so that the collar 37 may be moved upwardly along the angular sleeve 36 to any elected position, as indicated at 38' in Figure 2.

A spring 39 is positioned to exert a lift upon the block 35 when the collar 37 is moved to release said block. Before launching the bomb, therefore, the collar 37 is moved a space away from the block 35, the amplitude of movement determining the angle of camber of the fins when released from the holding means 32 upon the launching of the bomb.

Inserted within the body 20 at the end opposite the fins 30 is a projectile 40 having an explosive charge 41 therein, and any means as the slow match 42, for communicating ignition from the exploded charge 21 to the charge 41 at a time subsequent to the firing of the charge 21. The projectile 40 is held in position in any approved manner, as by a set screw 43, which, naturally, is sheared, as the projectile 40 is discharged.

The end of the body 20 carrying this projectile is also streamlined by a casing 44. Preferably, a rod 45 will extend from the apex of the shell 44 to the projectile 40 and by reason of nuts 46 and 47, aids in maintaining the projectile 40 in position.

The propeller fins 29 and nut 25 are held against accidental displacement by means of a cord or cable 48 which is attached to any part of the rack or craft structure, and is broken when the bomb is released. The cable passes through an eye 49 and is provided with a knot or other obstruction 50 after passing through a perforation in one of the fins 29.

60. The type shown at Figure 7 varies somewhat both in its structure and operation from the type shown at Figure 1. In this modification, the housing 20' also is provided with a charge of explosive 21' and a booster 22', as found in the structure shown at Figure 1. Also, a projectile 40' is inserted into the end of the body 20' in this case by means of a plug 51, which is attached to the projectile 40' by means of a threaded part 52, and all are maintained within the body 20' by the threaded connection 53 with the booster 22'. This projectile 40' is intended for contact explosion subsequent to the explosion of the explosive charge 21'.

The initial explosion is provided by means of a primer 54 communicating with the booster 22'.

and a firing pin 55 is normally supported out of contact with the primer by a spring 56. A hammer 57 is fulcrumed at 58 and pivoted to a rod 59 which is mounted to slide within a sleeve 60 secured rigidly to the body 20' and extending beyond the limits of the bomb, providing at its extreme end a foot 61 for contact. The rod 59 is threaded at 62, and a nut 63 is applied thereto to prevent the actuation of the hammer 57. This nut 63 is provided with vanes 64 whereby during the travel of the bomb the vanes 64 tend to unscrew the nut 63 to permit the sliding action of said rod upon contact.

As a further preventive of the accidental actuation of the firing pin 55 and the discharge of the explosive charge 21', a pin 65 is inserted through the conical shell 24' and provided with threads 66, the pin engaging under a head 67 and manually actuated by a knurled head 68. Prior to launching, the pin 65 is removed, depending upon the nut 63 to protect the hammer 57 against actuation. This type of bomb is also provided with fins 30', but unlike the fins 30 shown at Figure 1, these fins do not camber.

The stabilizing effect produced by the cambering of the fins, described in regard to Figure 1, is brought about in this instance by a gyroscope comprising a weighted wheel 69 journaled at 70, and through a train of gears 71 connected with the propeller 72 so that in the descent of the bomb, the air slip acting upon the propeller fins 72 will actuate the gyroscope to stabilize the trajectory of the bomb in the usual well known manner.

Both of the propellers 72 and 64 are held against rotation and for protecting purposes, by means of the cord or cable 48' which is connected, as before described, to any part of the aircraft or rack. In this instance, in addition to the eye bolt 49 and 50, as shown at Figure 1, a second loop or eye bolt 73 is provided upon the sleeve 60 and the other end of the cable 48' is provided with a knot or obstruction 74 after passing through a perforation in the propeller 64.

The projectile 40' is provided with a booster 75 with a primer 76 positioned to be fired by the firing pin 77, yielding supported by the spring 78. The firing pin 77 is provided with a contact head 79 which, however, is normally caged within a cap 80 to prevent accidental ignition. Before the bomb is launched, the cap 80 is manually removed whereby the head 79 is in position to make engagement with any engaged object.

In operation, the type shown at Figure 1 is racked by initially engaging the vanes 32 and moving the pin 38 upwardly a distance selected, depending upon the altitude. The cable 48 is attached to some part of the aircraft or crate. The bomb is launched from the rack in the usual well known manner, nothing herein being directed to the rack. When the bomb has been launched the cable 48 is still retained, at least in part, but is broken by the weight of the body to release the propeller 29. The descent of the bomb acting upon the fins 29 will unscrew the nut 25 and release the rod 26. This takes place during the descent of the bomb, and as soon as the nut 25 has been released, the bomb is in condition for action upon impact.

When the apex of the conical shell 44 engages with armor or the like, either with or without the presence of the rod 45, the resistance is such that the momentum of the rod 26 will engage the primer 23 to ignite the booster which in turn

ignites the charge 21, which is usual in such devices.

The rod 45 and casing 44 play an important part. Initial impact of the casing 44 with some surface, as the deck of a ship, imparts the necessary impulse through the rod 45 to ignite the projecting charge. However, a very small period of time is required for this functioning. During this period the body 20, under the influence of its momentum, will continue to move towards the surface being struck. This movement is resisted by the structure of the casing 44 as it is crumpled and destroyed. Hence, the projectile is fired substantially simultaneous with the lower end of the body 20 reaching the surface being struck.

Assuming that the impact has been against the armor of a ship, the initial discharge of the charge 21 will act against the projectile 40 and cause said projectile 40 to penetrate the armor and simultaneously to ignite the fuse 42. It will be obvious, of course, that the impact has crushed the shell 44 and rod 45, and that the projectile is, therefore, relatively free from hindrance to penetrate the armor. After penetrating, the charge within the projectile 40 will be ignited from the action of the fuse and the explosion of the projectile within the armor will demolish the adjacent articles.

The type shown at Figure 2 is not intended for penetrating armor, but for fortifications and other structures, more easily penetrated. The action of the bomb shown at Figure 2 will be the same as above described, except that the original detonation results from the engagement of the foot 61 with the structure. This, through the structure described, denotes the charge 21' to project the projectile 40' and its plug 51, which later impacts the structure by the foot 79, the cap 80 having been removed and the booster 15 ignited and through its action, the charge 41'.

In both types the initial discharge of the projectile is brought about by contact with the structure, the projectile being discharged thereby for subsequent explosion, in the one case by the time fuse—in the other, by contact, but in both instances the explosion occurring in the projectile subsequent to the initial discharge is intended as a demolition explosion.

While the projectiles 40 and 40' have been described as charged only with an explosive, it is obvious that gas or chemicals may be charged in these projectiles to operate in the usual well known manner upon the explosion of the charge necessary for the fragmentation of the projectile, whereupon the chemicals and the gas will be liberated.

It is notable that the pins 30 impart a spinning motion to the entire bomb which action maintains the bomb in position during falling. This spinning movement is also effective to hold the bomb in an upright position against any surface which

the bomb strikes until the charge therein is exploded to project the projectile. This is important as it insures an effective directioning of the projectile to better penetrate the surface it engages.

Of course, the aerial bomb illustrated may be modified and changed in various ways without departing from the invention herein set forth and hereinafter claimed.

I claim:

1. An aerial bomb comprising a hollow body, a projectile closing the forward end of the hollow body to form a chamber, a projecting charge within the chamber for projecting the projectile forwardly in the direction of flight of the bomb, a primer positioned to ignite the projecting charge, means to energize the primer upon impact of the bomb, and means to transmit the ignition from the projecting charge to the explosive charge in the projectile.

2. An aerial bomb comprising a hollow body for receiving a projectile charge, a projectile closing the forward end of the hollow body to form a chamber, a primer adapted to ignite the projecting charge, an explosive charge in the projectile, a fuse forming communication between the projecting chamber and the explosive charge, and means to energize the primer upon impact of the bomb with some other object.

3. An aerial bomb comprising a body having an explosive projectile, means to project the explosive projectile, fins carried by the bomb normally in a plane parallel with the axis of the bomb, means tending to pivot the fins, manual means for holding the fins against pivoting, and means to release the fins upon launching the bomb.

4. An aerial bomb comprising a body having a projecting charge and an explosive projectile, fins pivoted to the bomb, means tending to hold the fins parallel to the major axis of the bomb, and means tending to pivot the fins upon release of the holding means.

5. An aerial bomb comprising a body having a projecting charge and an explosive projectile, fins pivoted to the body, a block mounted to slide along the major axis of the bomb, means connecting the block tending to pivot the fins, a spring for actuating the block, and manual means for locking the block against action.

6. An aerial bomb comprising a hollow body, a projecting charge within the body, a projectile in the forward end of the body, an explosive charge within the projectile, means to employ impact to fire the projecting charge and the explosive charge in sequence, a gyroscope adapted to stabilize the flight of the bomb, and a propeller adapted to employ the air slip to actuate the gyroscope.

NORMAN N. BOOKER.
